INTERNAL COMBUSTION ENGINE

Andre J. Meyer, Detroit, Mich., assignor to Continental Motors Corporation, Detroit, Mich., a corporation of Virginia

Application May 30, 1930. Serial No. 457,625

31 Claims. (Cl. 123—75)

My invention relates to internal combustion engines and more particularly to a sleeve valve engine and the means for creating a maximum of turbulence in the combustion chamber.

5 In sleeve valve engines in which the fuel is injected into the cylinder through intake ports located in the cylinder wall, there is a tendency for the vaporized fuel to swirl. Various means have been devised to eliminate or control the swirling 10 action because increased turbulence may be obtained with a consequent increase in power if the fuel is prevented from swirling to a desirable degree.

It is an object of my invention to increase the 15 efficiency of an internal combustion engine of the sleeve valve type by providing means for preventing the incoming vaporized fuel from swirling in the cylinder to the extent that it would if the swirl is not controlled by the improvements 20 herein described.

Another object of my invention is to break up or modify the swirling action of the vaporized fuel in the cylinder of a sleeve valve engine by providing means for giving a directional force to 25 the incoming fuel to control its direction so that in the specific embodiment illustrated a part of the vaporized fuel flows in an opposite direction from the remainder of the fuel, said opposed fuel streams being arranged to meet and thus counter- 30 act or modify the tendency of the combustible gases to swirl.

For a more detailed understanding of my invention, reference may be had to the accompanying drawings which illustrate one form which my 35 invention may assume, and in which:

Figure 1 is a vertical sectional view through a sleeve valve internal combustion engine constructed in accordance with my invention and showing the improved reentrant cylinder head 40 structure depending within the cylinder,

Figure 2 is a horizontal sectional view taken substantially on the line 2—2 of Figure 1 and showing the cylinder head structure,

45 Figure 3 is a fragmentary sectional view taken at right angles to Figure 1, showing the reentrant portion of the cylinder head in elevation,

Figure 4 is a horizontal detail sectional view through a portion of the depending cylinder head 50 taken substantially on the line 4—4 of Figure 3,

Figure 5 is a fragmentary sectional view of a portion of an engine illustrating a cylinder head of modified construction,

55 Figure 6 is a horizontal sectional view taken on the line 6—6 of Figure 5,

Figure 7 is a detail sectional view taken on the line 7—7 of Figure 5,

Figure 8 is a fragmentary vertical sectional view illustrating a further modified form of construction, and

Figures 9 and 10 are horizontal sectional views taken on the lines 9—9 and 10—10 respectively of Figure 8.

The engine illustrated in the accompanying drawings comprises a cylinder block 10 of the usual construction, which is provided with a cylinder 11 provided respectively with the intake and exhaust ports 12 and 13 and intake and exhaust chambers 12' and 13' respectively, these chambers communicating with the usual intake and exhaust manifolds respectively designated by the reference characters 14 and 15. The intake manifold 14 and intake chamber 12' may be designated as the fuel mixture conducting means. As illustrated in the drawings, I 75 have provided a single sleeve valve means 16 which is ported for intake and exhaust, said sleeve ports cooperating respectively with the cylinder intake and exhaust ports 12 and 13, the sleeve intake port 17 being shown in the drawings as in registration with the cylinder intake port, and the piston A is located at approximately top dead center and at the beginning of the intake cycle. A cylinder head 18 is secured to the cylinder block and is provided with a reentrant head portion depending within the cylinder and spaced from the walls thereof to provide a sleeve pocket 20 adapted to receive the upper portion of the sleeve valve means 16. This depending cylinder head portion 19 extends below the top edge of the cylinder portion, as clearly shown in the drawings, for a purpose that will be hereinafter described in more detail. The depending cylinder head 18 includes a circular wall portion 18a depending within the cylinder and is constructed to provide a combustion chamber 18b preferably located concentrically with the cylinder axis. The depending wall portion 18a of the cylinder head is preferably undercut as at 18c and cooperatively associated with the sleeve valve means and piston A to provide an annular chamber 21 surrounding the combustion chamber 18b, this chamber 18b being located substantially internally of wall 18a and the chamber 21 being located substantially externally thereof. Even though in some instances it is desirable to form said outer annular chamber by recessing the piston, the said annular chamber may still be said to surround the combustion chamber 18b.

The incoming fuel is injected through the intake ports of the cylinder and the sleeve valve means, and the flow of the vaporized fuel is so controlled as to break up the tendency for this fuel to swirl within the cylinder. This is accomplished by providing deflecting means preferably carried by the cylinder head structure which deflects the incoming fuel and imparts thereto a directional force causing a portion of the fuel to flow in one direction and the remainder to flow in the opposite direction, these fuel streams being adapted to meet and set up a turbulence that counteracts or modifies the tendency of the fuel to swirl. With reference to Figures 1 to 4 inclusive, it is noted that the annular chamber 21 is constructed in the lower portion of the cylinder head structure, this annular chamber 21 extending around the circumferential lower edge of the reentrant head portion of the cylinder head structure adjacent to the cylinder wall and preferably within the limit of the sleeve valve means. Directly in line with the cylinder intake port, the cylinder head portion is provided with the recesses or grooves 22, 22a which are inclined to the vertical axis of the cylinder as clearly shown in Figure 3. The incoming fuel mixture admitted through the sleeve intake port is thus divided, a portion thereof being deflected by the groove 22 while the remainder is deflected by the groove 22—a, thus some of the fuel mixture is directed to flow in the annular chamber 21 in a direction opposite to the flow of the remaining fuel mixture, the tendencies of these fuel mixtures to swirl being eliminated or modified since the two fuel streams will meet at or near that portion of the cylinder or combustion chamber diametrically opposite to the intake port.

Preferably, the major portion of the fuel mixture introduced into the cylinder is acted upon and so divided as to direct the divided portions of the fuel mixture to flow in diverging directions; i. e., the fuel mixture divided portions tend to swirl in opposite directions and counteract or modify each other to fully eliminate the swirl or so control the swirl as to provide any desired resultant swirl. In the illustrated embodiment of my invention I have shown a construction in which substantially all the fuel mixture is acted upon and divided in such a way that portions of substantially equal mass are swirled in opposite directions, but I wish it to be understood that I am not limited to an equal mass distribution, since in some instances it may be more desirable to distribute or divide the incoming fuel mixture into portions of unequal mass for controlling the swirl to any desired degree. Further, the construction may be such as to control the swirl by an arrangement whereby said fuel mixture portions may be caused to swirl with different velocities. Thus broadly my invention relates to means for controlling or modifying the swirl and it may be noted that this action preferably takes place substantially throughout the entire intake stroke of the engine.

In Figures 5 to 7 inclusive a modified form of construction is illustrated which shows a partition or dividing flange 25 preferably carried by the cylinder head structure and cast integrally therewith. Part of the incoming fuel is directed to one side of this dividing flange or partition 25 while the remainder is directed to the other side of the partition. It is noted that the side faces of the dividing or partition wall 25, form the ends

of the annular chamber 21, the ends of this annular chamber being inclined to the axis of the cylinder as shown in Figure 5 so that the fuel stream directed into the annular chamber at one side of the wall or partition 25, is given a directional force, causing the same to flow in a direction opposite to the flow of the fuel delivered to the combustion chamber on the opposite side of this dividing wall or partition 25. It is noted that the cylinder head, as illustrated in the Figures 5 to 7 inclusive, and described above is provided with only one partition or dividing wall for imparting directional forces to the incoming fuel stream.

In Figures 8 to 10 inclusive, a further modified construction is illustrated and shows the cylinder head structure provided with the flanges or ribs 30 that are inclined at an angle to the cylinder axis as shown in Figure 8, these inclined ribs being spaced from the inside surface of the sleeve valve means and being preferably constructed of just sufficient depth as to induce the incoming fuel to flow in the desired direction.

It will thus be noted that I have provided a deflecting means which may be contained within the cylinder and also within the sleeve valve means mounted within the cylinder, which will be engaged by the stream of incoming fuel. This deflecting means will divide the fuel stream and so direct the same as to cause the same to flow in opposite directions, thereby in some instances setting up a turbulence within the cylinder so that the vaporized fuel will not have the tendency to swirl and in other instances modifying the swirl to any desired predetermined degree.

Further, it will be noted that I have provided a very simple means for controlling the swirl of the fuel mixture for accomplishing the purpose of my invention described above.

It will be apparent to those skilled in the art to which my invention pertains, that various modifications and changes may be made therein without departing from the spirit of my invention or from the scope of the appended claims.

What I claim as my invention is:

1. In a sleeve valve engine, a cylinder structure provided with fuel intake and exhaust ports, sleeve valve means for said cylinder having ports cooperating with the cylinder ports, a cylinder head structure having a portion depending within said cylinder and spaced from the walls thereof to form a sleeve pocket, said depending cylinder head portion and sleeve valve means cooperating to form bounding walls of a combustion chamber, and one of said bounding walls provided with fuel mixture conducting means associated with said engine means for deflecting a portion of the incoming fuel mixture to flow in a direction opposite to the flow of the remainder of the fuel mixture.

2. In a sleeve valve engine, a cylinder structure provided with fuel intake and exhaust ports, sleeve valve means for said cylinder having ports cooperating with the cylinder ports, a cylinder head structure having a portion depending within said cylinder and spaced from the walls thereof to form a sleeve pocket, said depending cylinder head portion and sleeve valve means cooperating to form bounding walls of a combustion chamber, fuel mixture conducting means associated with said engine and one of said bounding walls provided with means within the cylinder for deflecting a portion of the incoming fuel mixture to flow in a direction opposite to the flow of the remainder of the fuel mixture.

3. In a sleeve valve engine, a cylinder structure provided with fuel intake and exhaust ports, sleeve valve means for said cylinder having ports cooperating with the cylinder ports, a cylinder head structure having a portion depending within said cylinder and spaced from the walls thereof to form a sleeve pocket, said depending cylinder head portion and sleeve valve means cooperating to form bounding walls of a combustion chamber, 10 and one of said bounding walls provided with means for dividing said incoming fuel stream and directing one part of the fuel stream to swirl in the opposite direction from the other part of the fuel stream. 15
4. In a sleeve valve engine, a cylinder structure provided with fuel intake and exhaust ports, sleeve valve means for said cylinder having ports cooperating with the cylinder ports, a cylinder head structure having a portion depending within 20 said cylinder and spaced from the walls thereof to form a sleeve pocket, and means cooperating with the depending cylinder head portion for directing a portion of the incoming fuel to swirl in the opposite direction from the remainder of 25 the fuel.
5. In a sleeve valve engine, a cylinder structure provided with fuel intake and exhaust ports, sleeve valve means for said cylinder having ports cooperating with the cylinder ports, a cylinder 30 head structure having a portion depending within said cylinder and spaced from the walls thereof to form a sleeve pocket, and deflecting means carried by the depending cylinder head portion for directing a portion of the incoming fuel to 35 swirl in the opposite direction from the remainder of the fuel.
6. In a sleeve valve engine, a cylinder structure provided with fuel intake and exhaust ports, sleeve valve means for said cylinder having ports 40 cooperating with the cylinder ports, a cylinder head structure provided with a portion depending within said cylinder intake port, and deflecting means carried by the lower portion of said depending head for directing a portion of the 45 incoming fuel to swirl in the opposite direction from the remainder of the fuel.
7. In a sleeve valve engine, a cylinder structure provided with fuel intake and exhaust ports, sleeve valve means for said cylinder having ports 50 cooperating with the cylinder ports, a cylinder head structure having a portion depending within said cylinder and extended below the top edge of the cylinder intake port, said depending cylinder head constructed to provide an annular 55 chamber extending around the lower circumferential edge thereof, and means carried by said depending cylinder head for deflecting the incoming fuel to flow in opposite directions in said annular chamber.
8. In a sleeve valve engine, a cylinder structure provided with fuel intake and exhaust ports, sleeve valve means for said cylinder having ports 60 cooperating with the cylinder ports, a cylinder head structure having a portion depending within said cylinder and extended below the top edge of the cylinder intake port, said depending cylinder head constructed to provide an annular 65 chamber extending around the lower circumferential edge thereof, and deflecting means adjacent the cylinder intake port and carried by said 70 head for dividing the incoming fuel and directing one part thereof to flow in the annular chamber in a direction opposite to the direction taken by the remainder of the fuel.
9. In a sleeve valve engine, a cylinder structure 75 provided with fuel intake and exhaust ports, sleeve valve means for said cylinder having ports cooperating with the cylinder ports, a cylinder head structure having a portion depending within said cylinder and extended below the top edge of the cylinder intake port, said depending cylinder head constructed to provide an annular chamber extending around the lower circumferential edge thereof, and deflecting means inclined to the cylinder axis and carried by said head adjacent the cylinder intake port for deflecting a portion of the fuel to flow in said annular chamber in the opposite direction from the remainder of the fuel. 80
10. In a sleeve valve engine, a cylinder structure provided with fuel intake and exhaust ports, sleeve valve means for said cylinder having ports cooperating with the cylinder ports, a cylinder head structure having a portion depending within said cylinder and extended below the top edge of the cylinder intake port, said depending cylinder head constructed to provide an annular chamber extending around the lower circumferential edge thereof, and means for dividing the stream of incoming fuel and directing one part of said 90 fuel stream to flow around said annular passage in the opposite direction from the remainder of said fuel stream. 95
11. In an internal combustion engine having a cylinder and cooperating cylinder head, valve means associated therewith, a piston operating in said cylinder, said piston and cylinder head constructed and cooperating together to form outer bounding walls of a circumferential annular chamber located adjacent the cylinder wall, fuel mixture conducting means associated with said engine, and one of said bounding walls carrying means acting on the incoming fuel mixture to direct a portion of the fuel mixture to flow in the annular chamber in a direction opposite to the 100 direction taken by the remainder of the fuel mixture. 105
12. In an internal combustion engine having a cylinder and cooperating cylinder head, valve means associated therewith, a piston operating in said cylinder, said piston and cylinder head constructed and cooperating together to form outer bounding walls of a circumferential annular chamber located adjacent the cylinder wall, fuel mixture conducting means associated with said 110 engine, and one of said bounding walls carrying means acting on the incoming fuel mixture to direct a portion of the fuel mixture to flow in the annular chamber in a direction opposite to the direction taken by the remainder of the fuel mixture. 115
13. In an internal combustion engine of the sleeve valve type and including a cylinder having intake port means, fuel mixture conducting means associated therewith, a piston operable within the cylinder, sleeve valve means having 120 intake port means cooperating with the cylinder intake port means, said piston, sleeve valve means and cylinder cooperating to form the bounding walls of a combustion chamber and one of said combustion chamber walls provided with means 125 acting on the fuel mixture introduced to the engine during at least the initial portion of the intake period whereby to control the swirling of the fuel mixture. 130
14. In an internal combustion engine of the sleeve valve type and including a cylinder having intake port means, fuel mixture conducting means associated therewith, a piston operable within the cylinder, sleeve valve means having 135 intake port means cooperating with the cylinder 140
15. In an internal combustion engine of the sleeve valve type and including a cylinder having intake port means, fuel mixture conducting means associated therewith, a piston operable within the cylinder, sleeve valve means having 145 intake port means cooperating with the cylinder 150

intake port means, said piston, sleeve valve means and cylinder cooperating to form the bounding walls of a combustion chamber and one of said combustion chamber walls provided with means acting on the fuel mixture introduced to the engine for dividing the fuel mixture in said engine whereby to control the swirling of the fuel mixture.

15. In an internal combustion engine of the sleeve valve type and including a cylinder having intake port means, fuel mixture conducting means associated therewith, a piston operable within the cylinder, sleeve valve means having intake port means cooperating with the cylinder intake port means, said piston, sleeve valve means and cylinder cooperating to form the bounding walls of a combustion chamber and one of said combustion chamber walls provided with means acting on the fuel mixture for dividing at least the major portion of fuel mixture introduced to the engine and inducing one divided portion to swirl in one direction and another divided portion to swirl in the opposite direction whereby to control the swirling of the fuel mixture in the engine.

16. In an internal combustion engine of the sleeve valve type and including a cylinder having intake port means, fuel mixture conducting means associated therewith, a piston operable within the cylinder, sleeve valve means having intake port means cooperating with the cylinder intake port means, said piston, sleeve valve means and cylinder cooperating to form the bounding walls of a combustion chamber and one of said combustion chamber walls provided with means acting on the fuel mixture for dividing at least the major portion of fuel mixture introduced to the engine into portions of substantially equal mass and inducing one divided portion to swirl in one direction and another divided portion to swirl in the opposite direction whereby to control the swirling of the fuel mixture in the engine.

17. In an internal combustion engine of the sleeve valve type and including a cylinder having intake port means, fuel mixture conducting means associated therewith, a piston operable within the cylinder, sleeve valve means having intake port means cooperating with the cylinder intake port means, said piston, sleeve valve means and cylinder cooperating to form the bounding walls of a combustion chamber and one of said combustion chamber walls provided with means acting on the fuel mixture introduced to the engine to induce portions of the same to swirl circumferentially of the engine cylinder in opposite directions whereby to modify the tendency of the fuel mixture to swirl in said engine.

18. In an internal combustion engine of the sleeve valve type and including a cylinder having intake port means, fuel mixture conducting means associated therewith, a piston operable within the cylinder, sleeve valve means having intake port means cooperating with the cylinder intake port means, a cylinder head structure, said piston and cylinder head constructed and cooperating to form bounding walls of an annular chamber within the boundaries of the sleeve valve means, and one of said bounding walls provided with means acting on the fuel mixture introduced to the engine for dividing the fuel mixture whereby to control the swirling of the fuel mixture.

19. In an internal combustion engine of the sleeve valve type and including a cylinder having intake port means, fuel mixture conducting means associated therewith, a piston operable

within the cylinder, sleeve valve means having intake port means cooperating with the cylinder intake port means, a cylinder head structure, said piston and cylinder head constructed and cooperating to form bounding walls of an annular chamber within the boundaries of the sleeve valve means, and one of said bounding walls provided with means acting on the fuel mixture introduced to the engine for inducing portions of the fuel mixture to swirl in said annular chamber in opposite directions whereby to control the swirling of the fuel mixture in said engine.

20. In an internal combustion engine of the sleeve valve type and including a cylinder having intake port means, fuel mixture conducting means associated therewith, a piston operable within the cylinder, sleeve valve means having intake port means cooperating with the cylinder intake port means, a cylinder head structure, said piston and cylinder head constructed and cooperating to provide a primary combustion chamber and to form bounding walls of an annular chamber surrounding the primary combustion chamber, and one of said bounding walls provided with means acting on the fuel mixture introduced to the engine for dividing same and inducing portions of the fuel mixture to swirl in said annular chamber in opposite directions whereby to control the swirling of the fuel mixture in said engine.

21. In an internal combustion engine of the sleeve valve type and including a cylinder having intake port means, fuel mixture conducting means associated therewith, a piston operable within the cylinder, sleeve valve means having intake port means cooperating with the cylinder intake port means, a cylinder head structure having a wall portion extending inwardly of the cylinder and constructed to provide an inner combustion chamber and an outer annular chamber substantially surrounding the inner combustion chamber, and said cylinder head structure provided with means acting on the fuel mixture introduced into said annular chamber to induce counteracting swirling fuel mixture masses for controlling the swirling of the fuel mixture in the engine.

22. In an internal combustion engine of the sleeve valve type and including a cylinder having intake port means, fuel mixture conducting means associated therewith, a piston operable within the cylinder, sleeve valve means having intake port means cooperating with the cylinder intake port means, a cylinder head structure having a wall portion extending inwardly of the cylinder and constructed to provide an inner combustion chamber and an outer annular chamber substantially surrounding the inner combustion chamber, and deflecting means carried by said cylinder head for dividing the fuel mixture introduced to said annular chamber to induce a portion of the fuel mixture to swirl in said annular chamber in the opposite direction to another portion of the fuel mixture for controlling the swirling of same in the engine.

23. In an internal combustion engine having a cylinder and cooperating cylinder head, valve means associated therewith, a piston operating in said cylinder, said piston and cylinder head constructed and cooperating together to form bounding walls of a circumferential annular chamber located adjacent the cylinder wall, fuel mixture conducting means associated with said engine, and one of said bounding walls provided with means acting on the incoming fuel mixture
